UNITED STATES PATENT OFFICE.

JOHN J. TOKHEIM, OF THOR, AND EDWARD O. MANSFIELD, OF CEDAR RAPIDS, IOWA, ASSIGNEES TO THE TOKHEIM MANUFACTURING CO., OF CEDAR RAPIDS, IOWA.

MEASURING-PUMP.

SPECIFICATION forming part of Letters Patent No. 720,638, dated February 17, 1903.

Application filed May 13, 1902. Serial No. 107,207. (No model.)

To all whom it may concern:

Be it known that we, JOHN J. TOKHEIM, residing at Thor, in the county of Humboldt, and EDWARD O. MANSFIELD, residing at Cedar Rapids, in the county of Linn, State of Iowa, citizens of the United States, have invented certain new and useful Improvements in Measuring-Pumps, of which the following is a specification.

10 This invention relates to pumps adapted for the drawing and measuring of liquids, such as oil, the construction being such that a definite quantity may be pumped into a graduated transparent receptacle, where the amount 15 may be easily seen by a purchaser, and thence quickly emptied into a vessel for delivery to such purchaser.

The invention embraces certain improvements in the construction of a measuring-20 pump described in Letters Patent No. 640,336, issued to John J. Tokheim on the 2d day of January, 1900, the nature of which improvements will appear in the description and claims following, reference being had to the 25 accompanying drawings, in which—

Figure 1 is a side view of a pump embodying our invention, but without the drip-pan. Fig. 2 is a central vertical section of the same as seen from the front. Fig. 3 is an enlarged 30 section, showing detail of the measuring-reservoir and its connections, the overflow and the vent pipes.

In the main the pump is similar in construction to that shown and described in the patent above referred to. It comprises a pump-piston, the rod A of which is shown, a hand-lever B therefor, and a fulcrum-rod C, pivoted to a base D. The pump-rod passes down a pipe E, screwed into the bottom of the base, 40 to a cylinder (not shown) and thence by a suitable suction-pipe to the storage tank or reservoir. (Also not shown.) From the base to one side of the pump-rod rises a pipe F in direct communication with the pipe E by a 45 chamber D' in the base. At the upper end this pipe connects with a head G, the opposite end of which is provided with a bib H. In the top of this head is screwed the base I' of a reservoir I, adapted to hold a certain as-

certained volume of liquid. In practice this 50 reservoir is made of glass and graduated to denote fractional parts, as of a gallon. In the middle of the reservoir is a stand-pipe J, extending from near the dome of the reservoir to the base D, where it communicates 55 by a chamber D² with a drain-pipe K, leading back to the storage-tank. A suitable basin or pan L takes the drip from the bib. This is provided with a strainer L' and a little below it an inclined drip-collector L², emptying 60 into a discharge-pipe M.

The improvements which form the subject-matter of this invention will now be more particularly described.

In the patent above referred to it will be 65 seen that the overflow-pipe was provided below the base (which is usually secured to the floor) with an elbow and united by a lateral branch with a vertical pipe depending from the center of the drip-pan. In practice this was 70 found to be objectionable, as in many cases the joists and other timbers below the floor interfered with the pipe connections, making it difficult to mount and connect up the pump. In our improved base the overflow-pipe 75 screws into the top of the base and discharges its contents into a chamber D² formed therein. Another pipe screws into the bottom of the base and opens into the same chamber, and this serves as a drain-pipe to carry the 80 overflow back to the storage-tank. The same chamber connects with the drip-pan above the floor by a short pipe M, as clearly shown in Fig. 2. It will be observed that the bottom of the chamber D² is inclined at D³ to facilitate the outflow of the discharge from the 85 overflow-pipe.

Instead of the pipe-fittings and sections of pipe to which the measuring-reservoir was attached, as shown in said former patent, a single casting is now used. At one end is an elbow G' to take the upper end of the pipe F. The other end is screw-threaded to take a bib. About in the middle and below is a boss screw-threaded to take the upper end of the 90 overflow-pipe. Directly above it is a larger boss G², into which the nipple of the base I' screws. The upper end of the overflow-pipe 95

proper has a "running thread" for a considerable distance, so that the pipe may be run into the head far enough to allow the lower end of the pipe to clear the base as the head 5 is screwed on the pipe F. When thus screwed on, the overflow-pipe is run down, screwing into the base at the lower end, and is secured in proper position with a tight joint at the head by a lock-nut N. The upper end of the 10 pipe extends a short distance into the head, as best shown in Fig. 3, and to it is connected by a coupling J² a short section of pipe J', reaching nearly to the dome of the reservoir. This pipe is considerably smaller than the 15 nipple of the reservoir-base, thus leaving an annular opening for liquid from the pump to the reservoir. When the liquid rises above the upper end of the pipe J', it of course flows down the pipe and passes back to the storage- 20 tank, as above mentioned.

To facilitate the escape of the overflow, a vent-pipe O is mounted inside the overflow-pipe and terminates near the lower end of the same in a curved outlet O'. A separate section O², provided with a thimble O³, is adapted to slip a limited distance on the upper end of the pipe O and is held normally pressed upwardly by a spring P between the thimble and a collar O⁴. This admits of the upper 25 end of the vent-pipe reaching the dome of the reservoir and at the same time allows for variations in the heights of such reservoirs. Air is admitted to the vent-pipe through a notch O⁵.

30 It is to be understood that while the overflow-pipe J would of itself carry away the liquid rising above its upper end it would do so with considerable gurgling and more slowly than is desirable. The auxiliary vent allows 35

such overflow to run down the pipe J very 40 quickly.

Having thus described our invention, what we claim as new, and desire to secure by Letters Patent, is—

1. In a pump of the kind designated, a base 45 having a central hole in the bottom to take the delivery-pipe and pump-rod, a chamber communicating therewith, and having a hole opening upwardly to take a vertical continuation of the delivery-pipe, and a chamber op- 50 posite thereto, with holes opening upwardly, downwardly, and laterally, to take the overflow, drain and drip pipes, respectively, sub- stantially as described.

2. In a measuring-pump having supply and 55 overflow pipes substantially as described, a vent-pipe inside said overflow-pipe, extending a little distance above it and terminating in a curved outlet at the lower end near the end of the overflow-pipe.

3. In a measuring-pump having a reservoir and overflow-pipe, substantially as described, a vent-pipe comprising two telescoping sec- 65 tions, the lower one secured inside the over- flow-pipe, and having a collar or shoulder near its upper end, a spring above said collar, and a short section of vent-pipe telescoping the upper end of the fixed vent-pipe, with its vent- ed upper end touching the dome of the res- 70 ervoir.

In testimony whereof we affix our signatures in presence of two witnesses.

JOHN J. TOKHEIM.
EDWARD O. MANSFIELD.
